CLAIM

The design for a candy bar, substantially as shown and described.

DESCRIPTION

This application is a Division of 29/219,804 Dec. 23, 2004. FIG. 1 is a top perspective view of a candy bar showing our new design;

FIG. 2 is a top plan view thereof;

FIG. 3 is a front elevational view thereof, the rear elevational view being identical; and,

FIG. 4 is a right side elevational view thereof, the left side being identical.

The bottom of the candy bar forms no part of the claimed design.
